UNITED STATES PATENT OFFICE.

RUSSELL B. RICE, OF LAS VEGAS, TERRITORY OF NEW MEXICO.

MAIL-BAG LOCK.

No. 829,087.

Specification of Letters Patent.

Patented Aug. 21, 1906.

Application filed October 5, 1904. Serial No. 227,300.

To all whom it may concern:

Be it known that I, RUSSELL B. RICE, a citizen of the United States, residing at Las Vegas, in the county of San Miguel and Territory of New Mexico, have invented a new and useful Mail-Bag Lock, of which the following is a specification.

This invention relates to mail-bag fasteners, and has for its object to provide an improved fastener of this character which is especially arranged to be permanently carried by a mail-bag, so as to be in position for convenient access when it is desired to close and fasten the bag.

It is furthermore designed to embody the invention in the form of a hasp-lock capable of being snapped or sprung upon the locking staple or keeper of the bag and arranged to be automatically shifted into a position for removal from the staple or keeper by the introduction of a key to release the locking elements of the lock.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a perspective view of the upper or mouth portion of a mail-bag constructed for coöperation with the present form of lock with the latter attached thereto in an inoperative position. Fig. 2 is a detail plan view illustrating a step in the folding of the mouth of the bag to close the same. Fig. 3 is an enlarged sectional view taken through the mouth of the bag when folded and through the hasp-lock with the latter in locked position. Fig. 4 is a detail elevation of the device in its locked position. Fig. 5 is an end view thereof. Fig. 6 is a detail perspective view of the inner frame of the lock carrying the locking elements, parts of the frame being broken away to disclose said locking elements. Fig. 7 is an enlarged detail sectional view taken on the line 7-7 of Fig. 3 with a key in position to unlock the device. Fig. 8 is an enlarged sectional view on the line 8-8 of Fig. 5. Fig. 9 is a detail cross-sectional view of a modified form of hasp member.

Like characters of reference designate corresponding parts in each and every figure of the drawings.

The present invention includes a special construction of mouth for the mail-bag to coöperate with the locking element and also to permit of the bag being hung upon my holding-frame disclosed in my Patent No. 802,320, dated October 17, 1905.

The bag 1 may be formed of leather, canvas, or other suitable strong and flexible material and when open assumes a substantially rectangular shape. The front and back edges of the mouth of the bag are rendered rigid by reinforcing strips or plates 2 and 3, respectively, which are folded upon and riveted or otherwise secured to the material of the bag and are provided midway of their ends with registered longitudinal slots 75 or openings 4 and 5 formed through the respective strips and the bag. The material of each strip which is cut out to form the opening is bent back against the inner side of the bag, as indicated at 6 in Fig. 1. In addition to the intermediate openings the front and back edges of the bag are provided with corresponding transverse slots or openings 7 and 8, located at each side of the respective intermediate openings. The side edges of 80 the bag are similarly reinforced, each reinforcement consisting of a pair of members 9 and 10, which have their outer ends hinged to the respective front and back reinforcements, as indicated at 12 and 13, the joint 14 between the reinforcing members 9 and 10 being breakable inwardly and constituting a hinge by reason of the flexible nature of the bag, so as to permit of the mouth thereof being folded in the manner indicated in Fig. 2 95 of the drawings. Each of the side reinforcements is provided with a central longitudinal slot or opening 15 and transverse slots or openings 16, located at opposite sides of the intermediate opening and arranged to register with the corresponding openings in the front and back edges of the bag, as clearly indicated in Fig. 3.

At the front and back of the bag are transverse supporting-flaps 17 and 18, secured to the bag at or adjacent the lower edges of the reinforcements and provided near each end with the respective perforations or eyelets 19 and 20, designed for engagement with the supporting-pins of the bag-holding frame disclosed in my copending patent, hereinbefore referred to.

A closure-flap 21 is sewed or otherwise secured to the front of the bag at the lower edge of the reinforcement 2 and is of a size to fold over and embrace the mouth of the bag 5 when closed, as best indicated in Fig. 5. This flap is preferably formed of two layers or pieces of material and is provided at its outer end with a transverse metallic plate or bar 22, secured between the layers or plies of the 10 flap and provided with an intermediate substantially U-shaped or slotted keeper 23, projected at the inner side of the flap and disposed longitudinally of the plate, there being staples 24 carried by the plate at opposite 15 sides of the keeper and disposed transversely with respect thereto. The keeper and the staple are arranged to pass through the corresponding slots or openings in the reinforced edges of the mouth of the bag from the rear 20 side thereof in the folded condition of the bag, as clearly shown in Fig. 3, with the closed outer ends of the keeper and staples projected through the central side openings 25 and 26, respectively, formed in the inner edge 25 portion of the flap to register with the openings 4 and 7 at the front of the bag.

A very important feature of this invention will be understood by reference to Fig. 1 of the drawings, wherein it will be noted that 30 when the bag is open the mouth thereof is not obstructed by the staples 23 and 24.

The purpose of the reinforcing-strips at the mouth of the bag is to render the edges of the bag rigid, or comparatively so, in order that 35 the mouth of the bag may be held open or distended when supported upon my bag-holding frame and at the same time to facilitate the closing of the bag, which is accomplished by breaking inwardly the joints 14 of the 40 side-reinforcing strips and then closing the front and back edges of the bag together, as in Figs. 2 and 3, after which the closure-flap is folded over the mouth of the bag and the keeper and staples introduced through the 45 corresponding openings.

To maintain the mouth of the bag in its folded or closed condition, I employ locking means consisting of a hasp plate or member 27, which is provided with an intermediate 50 longitudinal slot or opening 28. At each side of the slot or opening 28 is a tongue or projection 29, cleft from the hasp and disposed at the inner side thereof in substantial parallelism therewith and capable of being slid 55 into the adjacent staple 24 by an endwise movement of the hasp. At each end of the hasp there is a flexible link or strap 31, which has its opposite ends riveted or otherwise fastened to the hasp and the closure-flap 21, as 60 indicated at 32, thereby to permanently connect the hasp with the closure-flap and at the same time permit of the required movement for engaging and disengaging the hasp with the staples or keepers of the bag.

Upon the outer side of the hasp and inclos-

ing the central opening 28 is a housing or casing 33, which is rigidly secured to the hasp by suitable fastenings and is designed to house and protect the working elements of the lock. Within this housing or casing is a 70 hollow frame 34, which carries the working elements of the lock and is open at its inner side, so as to register with the slot or opening 28 of the hasp, and thereby receive the keeper 23. An annular flange 35 extends around the 75 base of the frame and is received within a channel or rabbet 36, formed around the base of the housing or casing, whereby the frame is rigidly clamped between the casing and the hasp. Disposed longitudinally and externally upon one side of the frame 34 is a 80 spring latch-arm 37, riveted or otherwise fastened, as at 38, at one end to the frame with its free end portion projected beyond one end of the frame and offset inwardly toward the 85 frame, as at 39, to form a catch member. A beveled latch-head 40 is carried by the inner side of the latch-arm 37 and projects through an opening 41 in the adjacent side of the casing, so as to snap into engagement with the 90 keeper 23 in a manner as will be hereinafter described. At the opposite side of the frame is a detent consisting of a spring-arm 42, terminally secured to the frame, as at 43, and twisted, as at 44, to bring the outer free portion 95 of the shank into a plane at substantially right angles to the casing, with said free portion projected beyond the ends of the casing and then extended laterally across said end of the casing to form an arm 45, underlying the catch portion 39 of the latch-arm 37 and provided with a beveled head 46 to engage the catch portion 39 of the latch-arm 37, and thereby lock the same against outward movement away from the frame. Within the frame is a bowed spring 47, which has its inner end secured to the back of the frame, as at 48, and its free portion bowed forwardly and projected through the open side of the 100 frame, so as to lie within the slot 28 of the hasp-plate at what will be termed the "rear" 105 end of the frame and in rear of the latch-head 40. A trip-arm 49 is carried by the detent-arm 42 and has a lateral branch 50 projected through an opening 51 in the adjacent side 110 of the frame, so as to overlap the spring 47 in contact therewith, whereby the detent-arm 42 is controlled by the movement of the spring 47, as will be hereinafter described, to engage its catch-head 46 with the catch-terminal 39 of the latch-arm 37, so as to lock the latter against outward movement from the frame.

To provide for releasing the detent from the latch-arm, as shown in Fig. 7, a key channel or way 52 is formed transversely in the rear end of the casing or housing 33 in rear of the frame and above the detent-arm 45, so as to direct the key 53 into engagement with the upper side of the arm 45 to initially depress 115

120

125

130

the latter out of contact with the latch-arm and then to force the latch-arm away from the frame, and thereby withdraw the latch-head 40 from the keeper 23, and thus release the lock. The key is provided with a longitudinal bifurcation 54 to receive the pin or cross-bar 55, extending transversely across the keyway, the purpose of the pin or projection being to form an obstruction and prevent the insertion of a knife-blade or the like to release the elements of the lock.

When the bag has been closed and the closure-flap 21 folded over the mouth of the bag with the keepers projected through the respective slots, the hasp is applied and is moved in an endwise direction from right to left to engage the tongues or projections 29 with the staples 24 and to receive the keeper 23 within the central opening 28. The hasp is then further advanced, so as to move the catch-head 40 across the adjacent side of the keeper 23 until it snaps into engagement with the rear side of the adjacent arm of the keeper with said arm of the keeper embraced between the rigid head 40 and the spring 47, the latter being moved out of its normal position, and thereby placed under tension by engagement with the keeper. By reason of the spring 47 being moved out of its normal position it lifts the trip-arm 49, and thereby draws the detent 45 into positive engagement with the catch portion 39 of the latch-arm 37, thereby to positively lock the latch in engagement with the keeper.

To release the lock, the key 53 is introduced into the key channel or way 52, whereby it first depresses the detent-arm 45 and disengages the same from the latch-arm 37, and upon further inward movement of the key it strikes the projected end of the latch-arm and moves the same laterally sufficient to disengage the latch-head 40 from the keeper, whereupon the tension of the spring 47 is sufficient to automatically shift the hasp to the right, and thereby automatically release the projections 29 from the staples 24, and the hasp is then free to be swung away from the keeper 23.

It is preferred to have the hasp 27 in the nature of a channel-bar, as clearly indicated in Figs. 5 and 7, for the purpose of closely embracing the staples 24 to prevent lateral play of the hasp. This channel-bar form may be produced by longitudinal flanges 27^a or the hasp may be made arcuate in cross-section or semitubular, as at 27^b in Fig. 9, it of course being provided with offset tongues, one of which has been indicated at 29^a.

Having thus described the invention, what is claimed is—

1. In a lock, the combination with a hollow frame to receive a keeper, of a spring latch-arm secured externally to one side of the frame and provided with a latch-head working in an opening in the frame, and a detent

carried by the opposite side of the frame and having a detachable engagement with the latch-arm to retain the latter in locked position.

2. In a lock, the combination of a hollow frame to receive a keeper, a spring latch-arm carried externally by one side of the frame and projected at one end thereof, a head carried by the latch-arm and working in an opening in the frame, and a substantially L-shaped spring-detent carried externally by the opposite side of the frame with its transverse member extending across one end of the frame and detachably engaging the free projected end of the latch-arm to lock the same.

3. In a lock, the combination with a casing, of a hollow frame inclosed therein, the casing and the frame having registered openings for the reception of a keeper, a spring latch-arm carried externally by one side of the frame with its free end projected beyond one end of the frame, a latch-head carried by the arm and working in an opening in the frame, and a detent carried by the opposite side of the frame and projected across one end of the frame into engagement with the free end of the latch-arm, the casing being provided with a key-guideway leading to the detent and the free end of the latch-arm across one end of the frame.

4. In a lock, the combination of a hollow frame to receive a keeper, a latch-arm carried externally by one side of the frame with its free end projected beyond one end of the casing, a latch-head carried by the arm and working in an opening in the frame, a detent carried externally by the other side of the frame and detachably engaging the latch-arm, a movable member carried within the frame for contact with the keeper to be displaced thereby, and a trip member carried by the detent and disposed in the path of movement of the movable member to draw the detent into engagement with the latch-arm when the movable member is displaced.

5. In a lock, the combination of a hasp-plate having an opening to receive a keeper and provided at opposite sides of the opening with offset tongues upon the inner side of the hasp, a casing carried by the outer side of the hasp and inclosing the opening therein, a hollow frame rigidly secured within the casing and spaced from the casing, a spring latch-arm secured externally to one side of the frame with its free end projected at one end of the frame, a latch-head carried by the latch-arm and working in an opening in the frame, a substantially L-shaped spring-detent carried externally by the opposite side of the frame with one member disposed transversely across one end of the frame and having a catch-head for detachable engagement with the free end of the latch-arm, a bowed spring secured at one end within the back of the frame with its free end disposed in rear

130

of the latch-head and in position to be displaced by the keeper, and a trip member carried by the detent and provided with a transverse portion projected through an opening 5 in the frame into the path of the spring, the casing being provided with a key-guideway across one end of the frame and leading to the detent and the free end of the latch-arm.

6. The combination of a bag having corresponding openings in opposite sides thereof, a closure-flap carried by one side of the bag to embrace the mouth of the bag when closed, a keeper and staples at opposite sides thereof carried by the closure-flap to be inserted 10 through the corresponding openings of the

bag, an endwise-movable channel-bar hasp-plate loosely carried by the bag to embrace the keeper and the staples and provided with tongues for introduction through the staples, and a lock carried by the hasp-plate to engage the keeper and prevent endwise movement of the hasp from the keeper. 20

In testimony that I claim the foregoing as my own I have hereto affixed my signature in the presence of two witnesses.

RUSSELL B. RICE.
